US00D481250S

(12) United States Design Patent (10) Patent No.: US D481,250 S
Hassett (45) Date of Patent: * Oct. 28, 2003

(54) COMPACT DISC WALLET

- (75) Inventor: Eric S. Hassett, Golden, CO (US)
(73) Assignee: Case Logic, Inc., Longmont, CO (US)
() Term: 14 Years
(21) Appl. No.: 29/171,031
(22) Filed: Nov. 15, 2002
(51) LOC (7) Cl. 06-04
(52) U.S. Cl. D6/632; D3/301

(57) CLAIM

The ornamental design for a compact disc wallet, as shown and described.

DESCRIPTION

FIG. 1 is a front perspective view of a compact disc wallet showing my new design in an open position, the broken lines depicting environment and forming no part of the claimed design;

FIG. 2 is a front elevation view of the invention illustrated in FIG. 1 in a closed position;

FIG. 3 is a rear elevation view of the invention illustrated in FIG. 2;

FIG. 4 is a left elevation view of the invention illustrated in FIG. 2;

FIG. 5 is right elevation view of the invention illustrated in FIG. 2;

FIG. 6 is a top plan view of the invention illustrated in FIG. 2; and,

FIG. 7 is a bottom plan view of the invention illustrated in FIG. 2.
